COVER PLATE FOR HÆMACYTOMETERS

Carl Adolph Hausser and Anthony Adolph Hausser, Philadelphia, Pa.

Application October 14, 1933, Serial No. 693,664

4 Claims.

(Cl. 88—40)

Our invention relates to the transparent cover plates constituting an element of hæmacytometers and like devices, and the principal object of the invention is to provide a cover plate of generally improved characteristics.

A more specific object of the invention is to reduce the possibility of faulty contact between the cover plate and the cover plate supports by reducing the area of mutual contact to a practical minimum.

Another object of the invention is to reduce the possibility of flow of liquid from the liquid chamber to the cover plate supports by surface tension at the edges of the plate.

Still another object of the invention is to provide a cover plate that shall be less fragile than the plates previously employed.

A still further object of the invention is to provide a cover plate which shall be more likely to be within the required wave length accuracy than the cover plates previously used.

In the attached drawing:

Figure 1 is a view in perspective of a hæmacytometer equipped with a cover plate made in accordance with our invention;

Fig. 2 is a view in perspective of the cover plate;

Fig. 3 is an enlarged plan view of the hæmacytometer with the cover plate in position thereon, and

Fig. 4 is a section on the line 4—4, Fig. 3.

With reference to the drawing, 1 is a hæmacytometer having the usual spaced cover plate supports 2 and 3 and the intermediate table 4, the surface of which is slightly lower than the surfaces of the supports 2 and 3, so that when the cover plate 5 is placed upon said supports they form with the surface of the table 4 the narrow space 6 which constitutes the counting chamber. Moats 7 and 8 separate the supports 2 and 3 from the table 4, and moats 9 and 10 are also formed in the body of the hæmacytometer outwardly of the supports 2 and 3.

Heretofore it has been customary to produce the cover plates 5 in rectangular form, as illustrated by broken lines in Fig. 3. We have discovered that a material improvement in the characteristics of the cover plate may be realized by forming the plate in octagonal form, as illustrated, the dimensions of the sides of the cover plate being such that the end edges which adjoin the long sides of the hæmacytometer terminate, when the plate is in normal operating position, over the moats 7 and 8. While many other forms might be used to afford at least in

part the advantages of our invention, the octagonal form herein disclosed is considered the most desirable by reason of the fact that it is a form readily produced and one which combines a maximum stability of support for the cover plate with a minimum of contact area between the plate and the body of the hæmacytometer.

A cover plate made in accordance with our invention possesses several material advantages over the prior cover plate of rectangular form. It will be noted by reference to Fig. 3 for example that the rectangular cover plate, shown in broken lines, presents a continuous straight edge extending between the supports 2 and 3 and the counting chamber 6. In charging the counting chambers with the liquid, it is a frequent experience to have the liquid flow by surface tension along this straight edge of the cover plate to the cover plate supports 2 and 3. It will be apparent that a cover plate made in accordance with our invention lacks this straight edge extending from the counting chamber to either of the supports 2 or 3. The edge of the cover plate which overlies the counting chamber terminates in each instance over the moats 7 and 8, and the angular junction between this edge and the adjoining diagonal edges which extend to the supports 2 and 3 is sufficient to prevent flow of liquid by surface tension between the counting chamber and the said cover plate supports.

Another highly desirable characteristic of our cover plate resides in reduction in the chance of faulty contact between the cover plate and the cover plate supports, this by reason of the material reduction in the area of contact between these elements. From the illustration of Fig. 3, it will be apparent that the reduction in contact area between the cover plate and the cover plate supports is approximately 50%. This reduction in contact area between the cover plate and its supports also materially reduces the chance of the cover plate failing to be within the required wave length accuracy, since a curvature sufficient to render the cover glass inaccurate might well lie within the areas that have been eliminated by the octagonal design.

A further advantage of our design resides in the fact that the cover glass so formed is less fragile than the prior glasses by reason of the reduced area.

It will be apparent that there may be some modification in the form of the cover plate without departure from the invention.

We claim:

1. In a haemacytometer, the combination with the counting chamber table and the support surfaces separated by moats from said table, of a cover plate adapted to rest on said surfaces and to overlie the table, the edges of said plate extending across the table terminating at both ends at points overlying the said moats.

2. In a haemacytometer, the combination with the counting chamber table and the support surfaces separated by moats from said table, of a cover plate adapted to rest on said surfaces and to overlie the table, the edges of said plate extending across the table terminating at both ends at points overlying the said moats and the edges of the plate adjoining the edges first named forming with the latter obtuse angles.

3. A cover plate for haemacytometers of the type comprising a counting chamber table and cover plate support surfaces separated by moats

from said table, said cover plate being formed with edges adapted in assembly to extend transversely across said table, and said edges terminating at points above said moats and forming substantial angles with the adjoining edges of the cover plate.

4. A cover plate for haemacytometers of the type comprising a counting chamber table and cover plate support surfaces separated by moats from said table, said cover plate having end edges adapted in assembly to extend transversely across said table and to terminate at points above said moats, and side edges bounding those portions of the cover plate adapted to engage the support surfaces, and edges connecting the said side edges with the terminal ends of the end edges and forming obtuse angles with the latter.
